UNITED STATES PATENT OFFICE.

MARC-ANTOINE PATTAY AND EUGÈNE JAQUEMOT, OF GENEVA, SWITZERLAND,
ASSIGNORS TO CHARLES VON DER WEID, OF GENEVA, SWITZERLAND.

ELECTRIC-INCANDESCENT-LIGHTING APPARATUS.

1,346,671.

Specification of Letters Patent.

Patented July 13, 1920.

Application filed September 4, 1919. Serial No. 321,605.

To all whom it may concern:

Be it known that we, MARC-ANTOINE PATTAY, tradesman, and EUGÈNE JAQUEMOT, mechanician, citizens of Switzerland, residing at Geneva, Canton of Geneva, in the Confederation of Switzerland, have invented certain new and useful Improvements in Electric-Incandescent-Lighting Apparatus, of which the following is a specification.

10 This invention relates to a lighting apparatus and more particularly to an electric lighting apparatus especially designed for use in motor vehicles, although, as will be understood, its use is not so limited. The 15 invention relates still more specifically to that type of electric lighting apparatus in which relatively small electric lamp bulbs are employed. These small electric lamp bulbs are usually manufactured with a screw 20 threaded stud adapted to be received in a socket for completing the circuit through the filament of the lamp bulb. Due to the relative size, however, of these screw studs the same are not entirely uniform and this 25 applies also to the socket members in which these screw studs are adapted to fit, the result being that in many instances the contact between the screw stud and the socket is not sufficiently good to make the proper 30 contact for closing the circuit, and the object of this invention is to overcome these difficulties.

In carrying out the invention, we employ a holder adapted to receive the lamp socket, 35 together with a lamp device for receiving and engaging the screw stud of the lamp bulb in order to maintain the same in position with a perfect contact, as will be hereinafter more particularly described.

40 In the drawing:

Figure 1 is an elevation and partial cross section illustrating the lighting apparatus made in accordance with this invention.

Fig. 2 is a central longitudinal cross section illustrating the socket member and the parts for engaging the stud or shank of the lamp bulb.

Fig. 3 is an elevation of the clamp member, and

50 Fig. 4 is an elevation of the gland.

Referring to the drawing, it will be seen that in carrying out this invention, we preferably employ a holder or body member *a* which may be cylindrical or of any other 55 configuration and made of any suitable ma-

terial. At one end of the holder *a* the end *a'* thereof terminates in an internal socket or sleeve indicated at *a''*. At the opposite end of the holder *a*, the same interiorly is provided with a groove *a''* adapted to receive a wire *d* to act in conjunction with a lens *c* for maintaining the latter in position in the holder. On diametrically opposite sides of the holder *a* the same may be fitted with lugs to receive screws *d'* passing 60 through the ends of a bracket *e* which, by means of a suitable bolt or otherwise, may be secured to the rod or frame *f* or other part of a vehicle or other structure.

The lamp bulb is indicated at *g*, and as is customary is provided with a screw stud *g'*. This is adapted to be received in one end of a clamp sleeve *h*. As clearly shown in Fig. 3 this clamp sleeve *h* is screw threaded exteriorly as indicated at *h'* at one end thereof and at the other end is provided with a flaring extremity as indicated at *h''* and in which there are slots *h''* extending appreciably into the screw threaded body portion of the sleeve. Associated with these 80 members I also employ a collar *i*. This is provided at one end with a flange *i'* adapted to receive the flared portion *h''*, and in order to make the collar more resilient it may also be slotted as indicated at *i''*.

Together with these parts there is also employed a cap *j*. This is fitted with a bushing *k* connected to a plug *l*, the parts being associated as clearly shown in Fig. 2 of the drawing, in which, as will be seen, the collar *i* is adapted to fit over the outer portion of the cap *j* with the end thereof abutting against a shoulder provided therefor on the outer portion of this cap, while interiorly the cap *j* is screw threaded so as to receive 95 the body portion of the sleeve *h*. The parts of the lamp structure as thus assembled are indicated at *b*. Now, it will be apparent that when the cap *j* is turned so as to free the same or partially free the same from the screw threaded body portion of the sleeve *h* the outer flaring and slotted end of the sleeve *h* will readily receive the screw stud of the lamp bulb, and when the screw stud of the lamp bulb is thus received in the flared end of the sleeve *h* the cap *j* may be turned in the opposite direction so as to draw the sleeve *h* within the same, carrying the lamp bulb with it and causing the flared end portion *h''* of the sleeve to securely engage the 100 105 110

screw stud of the bulb by being forced into the flanged end of the collar *i*.

As indicated in the drawing, one terminal to the lamp may be secured in the bracket *e* as indicated at *m'* with a lead wire *m* extending thereto, while the other lead wire as indicated at *n* may be suitably connected to the plug member *l*.

We claim as our invention:

- 10 1. An electric lighting device, comprising a cap, a sleeve member having a screw threaded body portion adapted to be received in the said cap, and a flared slotted portion adapted to receive the screw stud of a lamp bulb, and a slotted cylindrical collar adapted at one end to fit over a portion of the said cap and provided at the opposite end with an internal flange adapted to engage with the flared portion of a sleeve so that when 15 the sleeve is turned down in the cap the flanged portion of the collar will engage the flared portion of the sleeve to force the same against the screw stud of the lamp bulb to hold the same in position.
- 20 2. An electric lighting device comprising a holder having a lamp socket at one end and a lens at the other end, a lamp fitting

consisting of a cap, a sleeve having a screw threaded body portion adapted to be turned into the said cap, and a flaring slotted portion adapted to receive a screw stud of a lamp bulb, and a collar adapted at one end to be received on a portion of the said cap and abut against a shoulder provided therefor on the said cap, the said collar being provided at its opposite end with an internal flange adapted to bear against the flaring portion of the sleeve so that when the sleeve is turned into the cap the flaring portions of the sleeve will be engaged by the internal flange on the collar to cause the flaring portions of the sleeve to engage the screw stud of a lamp bulb to hold the same in position, the said clamp fitting being adapted to be received within the socket member of the 45 said holder.

In testimony whereof we affix our signatures in presence of two witnesses.
